UNITED STATES PATENT OFFICE

ANDREW SWANFELDT, OF LOS ANGELES, CALIFORNIA

SUN-BATH CABINET

Application filed April 23, 1927. Serial No. 186,082.

This invention relates to sun bath cabinets, and the principal object is to provide a light weight, portable and collapsible cabinet comprising a suitable frame and a flexible covering thereon, open at the top so as to admit the sun's rays directly to the interior of the cabinet, and preferably covered with some suitable material such as netting which will obscure the interior of the cabinet from view, 10 and yet admit the sun's rays thereinto.

Another object is to provide a sun bath cabinet having one or more sides tiltable so as to accommodate the cabinet to the angle of the sun's rays.

15 A further object is to provide means within the cabinet, and preferably disposed horizontally thereacross, for selectively exposing a portion or portions of the human body when in a reclining position in the cabinet directly 20 to the sun's rays, and for covering other portions of the body to prevent contact of the sun's rays therewith.

Other objects will appear as the description progresses.

25 I have shown a preferred form of invention, subject to modification within the scope of the appended claims, in the accompanying drawings, in which:

Fig. 1 is a perspective view of my improved 30 cabinet with the top covering omitted, and with the flexible side coverings broken away to show structural details.

Fig. 2 is a perspective view of the assembled cabinet, partly broken away to show 35 the interior thereof.

Fig. 3 is a fragmentary section on line 3—3 of Fig. 1; and

Fig. 4 is a fragmentary section on line 4—4 of Fig. 1.

40 Fig. 5 is an enlarged perspective view of a detail of the toggle connections for collapsibly connecting the frame members.

Fig. 6 is a fragmentary section on line 6—6 of Fig. 1.

45 It will be understood that in modern therapeutics especially for the treatment of tuberculosis patients, and generally for other diseases, exposure to the sunlight has been found to be greatly beneficial, and due to this 50 fact I have provided an improved cabinet

which may be transported from place to place, and readily set up in places where the sunlight is unobstructed, the cabinet being arranged so that ample ventilation will be provided and at the same time accommodate 55 the cabinet to the varying angles of the sun's rays.

It is especially desired that the entire structure be such that it may be readily collapsed and folded and rolled into a small bundle 60 of light weight.

Accordingly, it is desirable to provide a frame of either light strips of wood or metal, or both wood and metal, with fabric coverings 65 of canvas or other densely woven fabric so as to obscure the interior of the cabinet from view from the outside. The fabric coverings may be provided in any one of a number of suitable colors to suit the varying tastes, and in some cases to provide certain color tones 70 which will tend to compose a patient while being treated within the cabinet.

It is recognized in modern practice that 75 colors have certain influences on the condition and functioning of the human body, at least to an extent that certain colors will compose and rest the body and mind of a patient, while other tones will distract and render a patient to a certain extent nervous, or of an unsatisfactory state of mind, tending to off-set the value of any kind of treatment, especially for nervous disorders.

Referring particularly to Fig. 1, it will be observed that my invention in its preferred 85 form embodies upright members A and α at one end and similar members A' and α' at the other end, all of which are of substantially similar character except as may be hereinafter described.

The members A and α and A' and α' are 90 transversely connected at their lower ends by toggle links B and B' which are hingedly connected together near their inner ends at points 1, 1, etc., the outer ends of said members being pivotally attached to the lower portions 95 of the standards, A, α , A' and α' , respectively. Likewise the upper ends of said standards are similarly connected transversely of the cabinet by similar toggle bars b and b', which are pivotally connected near their inner ends 100

at points 2, and at their outer ends to the standards.

Members A and A', and a and a' are respectively connected longitudinally of the cabinet by toggle bars C and C' pivotally connected together near their inner ends at points 3, and pivotally connected at their outer ends at points 4 to the lower ends of the standard. The upper ends of said standards are similarly connected longitudinally at the two opposite sides by similar toggle bars D and D' pivotally connected at points 5 near their inner ends and at points 6, 6, etc., at their outer ends to the upper ends of the standards, respectively.

The toggle bars b and b' are diagonally braced and are detachably connected with the standards by means of brace rods, e, e, etc., which are pivotally held at their upper ends 7 in the bars b and b' and are detachably connected at their lower ends 8 by inserting said ends in suitable bores formed in the edges of the standards A and A', and a and a'. Similarly the toggle bars D and D' are connected by diagonal brace rods E, E, etc., with the sides of the standards in a similar manner.

All of said braces and toggle bars, as shown in Fig. 1, serve to provide a rigid, light-weight frame for the purpose of supporting a fabric covering of suitable character, as at F, which may be attached to the standards A and A', etc., by means of buttons 9 secured to the standards in sufficient number and in spaced relation, and adapted to extend through metal covered openings 10, 10, etc., on the cover f and to be held by means of pivoted members 11, such as are used for similar purposes in other devices and well known in the art.

The main part of the frame is adapted to be enclosed on two ends and one side, or otherwise, by the fabric f which may be formed in one or more sections and so arranged that at one of the corners the fabric may be folded back so as to provide entrance to and exit from the interior of the cabinet.

On one side of the cabinet, or on two opposite sides if necessary, I may provide a tiltable side frame composed of inclined end members F, F, in the plane of and pivotally attached to the standards A and A' by means of hinges 12 connecting the same near the lower ends of members F and A and A', so that the upper free ends of the members F may be moved inwardly and outwardly with respect to the members A and A'.

The upper ends of said members F, F are connected together by means of the toggle bars D and D', such as are used for connecting members A and A', and a covering f' of fabric is suitably attached to the tiltable frame extending over the side and ends thereof and connected by means of the buttons 9, 9, etc., to the ends of the main frame at the members A and A'.

The tiltable frame is adjusted as to inclination by means of one or more operating bars O which may be pivotally attached at their outer ends to the members F and adjustably connected at their inner ends to the members A or A', or both of said members.

Member O has a finger piece O' and notches 13, 13 formed in one edge thereof are adapted to engage the pin R extended inwardly from the member A or A', so that said member may be adjusted for varying the angle of the tiltable frame by engaging selected ones of the notches 13 with the pin R. This adjustment is necessarily made from the interior of the cabinet.

The cabinet is formed with an open top which is adapted to be covered by a suitable netting as at T, reinforced at the edges by a fabric strip as at t, extending therearound and adapted to overlie and to be attached to the upper portion of the frame by means of the buttons 9, as shown in Fig. 2. The top T and the angular end portions of the fabric covering f' are provided with sufficient surplus material so that the tiltable frame may be inclined outwardly to a maximum extent, and when the same is moved inwardly and the angle thereof decreased, the surplus material will be folded as shown in Fig. 1.

The cabinet may be provided with a suitable connection as at G, positioned therewithin, and above the level of the connection I may provide one or more roller curtains as at H and H' horizontally disposed in overlapping planes if two curtains are used, so that the space 13, 13 between the inner edges of said curtains may be varied in position and as to width for covering certain portions of the human body disposed on the cot G and for exposing certain other selected portions of the body to the action of the sun's rays which enter the cabinet through the top netting T.

The curtains H and H' are mounted on suitable rollers r and r' such as are used in window curtains, and are spring held as in the case of window curtains and ratchet operated. It is desirable to arrange curtains H and H' so that the same may be operated by a patient when reclining on the cot G, and to this end I provide on each of the opposite sides of the cabinet internally of the fabric covering f' pairs of continuous cords I and I' and i and i' adapted for connection, respectively, with the opposite ends and inner portions of the curtains H and H'.

The curtain H is connected at a point N near the inner edge thereof with the upper portion of a cord I which operates over a pair of pulleys as at J, one of which is mounted on the inner side of each of the members A and A' below the plane of the curtain H. An opposite portion of the curtain H is connected at N' with the upper portion of the parallel cord I' similarly operated over pulleys as at J'.

The curtain H' is similarly connected at opposite points as at P, with the lower portions of cords i and i' which operate over pulleys K and K', respectively, attached to the standards at the opposite sides of the cabinet. The rollers H and H' are mounted at opposite ends on the standards A and a and A' and a' on brackets h and h', respectively, similar to those used in connection with window shades. Thus the curtains H may be operated by pulling the cords I and I' simultaneously, while the curtain H' may be similarly operated by pulling the cords i and i'.

Referring to Fig. 5 it will be observed that the toggle bar sets B, B', b, b', C, C' and D, D' are similarly operated and connected together and with the standards, and differ only as to length. The members of each set, as shown in Fig. 5, are provided with abutments 15 and 15' which abut the inner ends of the members, as at D and D' for limiting the movement of the toggle bars and for holding the same in true horizontal planes when extended for use.

It will be noted that the fabric coverings f and f' do not extend quite to the ground or surface on which the cabinet is adapted to rest, so that a narrow space may be provided at the lower edges of said coverings to permit the entrance of air for affording ventilation to the interior of the cabinet.

The entire cabinet structure may be collapsed and rolled into a compact bundle by removing the fabric coverings f and f' by unbuttoning the same from the buttons 9, 9, etc. Thereafter the diagonal braces E, E, etc., and e, e, etc., at the sides and ends of the cabinet, respectively may be disengaged at their lower ends from the standards A, A', a and a' and from the toggle bars D, D', and b and b' at the top of the cabinet bent downwardly and inwardly. Likewise, the toggle bars B and B' and C and C' are bent upwardly and inwardly while the toggle members D and D' are bent downwardly and inwardly. Thus the standards A, A', a and a' will be moved inwardly so that the adjacent inner sides thereof may be substantially in abutment, while the toggle bars will fold inwardly and outwardly, as the case may be, of the standards so that the space occupied by the collapsed frame will be substantially that of the members A, A', a and a' and F, F, when arranged in close relation with respect to each other.

When the frame is collapsed as stated, the same may be neatly and compactly rolled into the fabric covering f and f', so that the same may be transported from place to place readily and will provide a light-weight bundle or package.

What I claim is:

1. A sun bath cabinet including a collapsible frame composed of upright members at the corners pivotally and collapsibly con-

nected together at their upper and lower extremities, one side of said frame being tilttable at selected angles with respect to said upright members, a fabric covering extended around the sides of and secured to said frame for providing an open top for admitting the sun's rays to the interior of the cabinet, and means operable from the interior of the cabinet for adjusting the angle of said tilttable side. 70

2. A sun bath cabinet comprising a collapsible frame, a fabric covering on the sides thereof, and an adjustable curtain operably mounted on said frame for movement in a horizontal plane intermediate the top and bottom of said frame, said curtain adapted to be disposed over a body within the cabinet above a body disposed in said cabinet, whereby selected portions of said body may be exposed directly to the sunlight admitted through the top of said frame. 75

3. A sun bath cabinet including a frame having upright members at the corners, and braces connecting the same at the sides and ends, a fabric covering the sides thereof, said cabinet arranged to receive a body disposed in a reclining position therein, and a pair of curtains adjustably mounted in horizontal planes within said cabinet on said frame and above said body, and means for operating said curtains for exposing selected portions of the body to the sunlight admitted from the top of said cabinet. 80

4. A sun bath cabinet including a collapsible frame, a fabric extended around the sides thereof, said cabinet arranged to receive a body disposed in a reclining position therein, a pair of curtains adjustably mounted in horizontal planes within said cabinet on said frame and above said body, means for operating said curtains for exposing selected portions of the body to the sunlight admitted from the top of said cabinet, said cabinet including an adjustable side composed of members hinged at the bottom to said frame and providing a variable opening at the top of the cabinet for accommodating the cabinet to the varying angles of the sun's rays. 100

5. A sun bath cabinet comprising a frame having rigid vertical members at the corners, sectional and hingedly connected rails collapsibly connecting the upper and lower ends of said rails longitudinally and transversely, a tilttable frame hingedly connected at its bottom on one side of the cabinet and to the lower portions of a pair of said vertical members, a fabric covering held on said frames for enclosing the sides thereof, said covering being extensible at the ends for permitting the tilting of said second frame for adjusting the cabinet to the varying angle of the sun's rays. 115

6. A sun bath cabinet comprising a frame having rigid vertical members at the corners, sectional and hingedly connected rails collapsibly connecting the upper and lower ends 120

of said rails longitudinally and transversely, a tiltable frame hingedly connected at its bottom on one side of the cabinet and to the lower portions of a pair of said vertical members, a fabric covering held on said frames for enclosing the sides thereof, said covering being extensible at the ends for permitting the tilting of said second frame for adjusting the cabinet to the varying angle of the sun's rays, and means within the cabinet for adjusting the angle of said second frame.

7. A sun bath cabinet comprising a frame having rigid vertical members at the corners, sectional and hingedly connected rails collapsibly connecting the upper and lower ends of said rails longitudinally and transversely, a tiltable frame hingedly connected at its bottom on one side of the cabinet and to the lower portions of a pair of said vertical members, a fabric covering held on said frames for enclosing the sides thereof, said covering being extensible at the ends for permitting the tilting of said second frame for adjusting the cabinet to the varying angle of the sun's rays, and means extensible horizontally in said cabinet and supported on said frame intermediate the top and bottom thereof for selectively exposing portions of a person to the sunlight.

8. A sun bath cabinet comprising a frame having rigid vertical members at the corners, sectional and hingedly connected rails collapsibly connecting the upper and lower ends of said rails longitudinally and transversely, a tiltable frame hingedly connected at its bottom on one side of the cabinet and to the lower portions of a pair of said vertical members, a fabric covering held on said frames for enclosing the sides thereof, said covering being extensible at the ends for permitting the tilting of said second frame for adjusting the cabinet to the varying angle of the sun's rays, and a fabric covering over the top of said cabinet formed of light transmitting material obscuring the interior of the cabinet from view, said top covering being connected with both of said frames and extensible to accommodate itself to the tilting of said second frame.

9. A sun bath cabinet comprising a collapsible frame having vertical members at the corners, folding sectional braces connecting the vertical members on the sides and ends of the cabinet and near the upper and lower extremities of the vertical members, and a tiltable frame on one side of the cabinet composed of members hinged near their lower extremities to the lower portions of a pair of said vertical members, and folding braces connecting the upper portions of said tiltable members, and means for adjusting the angle of said tiltable members from within the cabinet.

10. A sun bath cabinet comprising a collapsible frame having vertical members at the corners, folding sectional braces connect-

ing the vertical members on the sides and ends of the cabinet and near the upper and lower extremities of the vertical members, and a tiltable frame on one side of the cabinet composed of members hinged near their lower extremities to the lower portions of a pair of said vertical members, and folding braces connecting the upper portions of said tiltable members, means for adjusting the angle of said tiltable members from within the cabinet, and a vision-proof fabric covering the sides and ends of said cabinet and also covering said tiltable side and formed so as to enclose the angular spaces between the vertical members and the tiltable members at one side of said cabinet, for the purpose described.

11. A sun bath cabinet comprising a collapsible frame having vertical members at the corners, folding sectional braces connecting the vertical members on the sides and ends of the cabinet and near the upper and lower extremities of the vertical members, and a tiltable frame on one side of the cabinet composed of members hinged near their lower extremities to the lower portions of a pair of said vertical members, and folding braces connecting the upper portions of said tiltable members, means for adjusting the angle of said tiltable members from within the cabinet, and a pair of curtains horizontally disposed in the cabinet and mounted on said vertical members intermediate the ends thereof, and means for operating said curtains for exposing selected portions of a person when held in a reclining position within the cabinet below the curtains.

12. A sun bath cabinet comprising a collapsible frame having vertical members at the corners, folding sectional braces connecting the vertical members on the sides and ends of the cabinet and near the upper and lower extremities of the vertical members, and a tiltable frame on one side of the cabinet composed of members hinged near their lower extremities to the lower portions of a pair of said vertical members, and folding braces connecting the upper portions of said tiltable members, means for adjusting the angle of said tiltable members from within the cabinet, and means for detachably connecting and bracing said end members and said braces for supporting the cabinet in extended position.

ANDREW SWANFELDT.
